SECTIONAL AUTOMOBILE RADIATOR

Filed Oct. 8, 1927

UNITED STATES PATENT OFFICE

CLAUDE D. LARMER AND BENJAMIN E. DETTMAN, OF CHICAGO, ILLINOIS

SECTIONAL AUTOMOBILE RADIATOR

Application filed October 8, 1927. Serial No. 224,817.

This invention relates to an improved radiator structure particularly for internal combustion engines, but also useful for space heating or cooling purposes.

It is an object of this invention to provide an improved form of sectional radiator structure that allows more flexibility to meet the weaving and vibration encountered in automotive service. The sectional structure also allows replacement of a damaged section without disturbing the air fins of other sections and eliminates head sheets and soldered joints. The sectional structure provides a much longer path for water travel thus securing greater cooling capacity, and the distance of travel can be varied to suit the requirements of the installation by the addition or removal of sections as desired.

It is also an object of this invention to provide an improved sectional radiator structure wherein each section is made up of interchangeable end boxes connected by thin walled flattened tubing having fins assembled thereon with spacing flanges integral with the fins.

Other and further important objects of this invention will be apparent from the disclosures in the specification and the accompanying drawings.

This invention (in a preferred form) is illustrated in the drawings and hereinafter more fully described.

On the drawings:

Figure 1 is a front elevation of a radiator embodying the features of this invention.

Figure 2 is an enlarged vertical section on the line II-II of Figure 1.

Figure 3 is a plan view of one unit.

Figure 4 is a sectional view on the line IV-IV of Figure 3.

Figure 5 is a sectional view on the line V-V of Figure 4.

As shown on the drawings:

The automotive type of radiator chosen for illustration comprises a bottom tank 10 having a removable clean out plate 11 on the bottom, and mounting brackets 12, on either end, the cold water outlet 13 being indicated in dotted lines on Figure 1. A top tank 14 has a filler opening 15 and a water inlet 16

also indicated by dotted lines, the water or steam from the top tank flowing into the tube sections through an opening 17 on the left hand end of the bottom.

The top and bottom tanks are connected by a tortuous cooling water passage extending back and forth through a series of radiating units comprising side boxes 18 having a passage 19 opening on two adjacent surfaces, each unit comprising two side boxes, one of which has an opening 20 for the passage 19 on its upper face and the other a similar opening 21 on its bottom face, the two boxes being identical but reversed. The boxes each have openings 22 on the sides facing each other to receive the ends 23 of oblong cross section tubes 24 which make water tight seals with the boxes due to a forced and expanded seat thereon. The various units are assembled in pairs as shown in Figure 4 with gaskets 25 between the boxes and the required number of sections are assembled on long bolts 26 connecting the top and bottom tanks and passing through holes 27 in the boxes. Side pieces 28 are used as covers for the boxes 18 and are clamped in position between the top and bottom tanks by the bolts 26.

Each tube 24 has a series of fins 29 pressed thereover to increase the radiating surface, these fins having flanges 30 struck from the hole in both directions parallel to the tubes, the flanges on either side of the fin alternating to meet similar flanges on the next fin to assure uniform spacing thereof while maintaining the erectness of each fin. The fins on adjacent tubes are staggered by omitting one fin from alternate tubes to improve the air circulation therethrough.

In the operation of this radiator the hot water from the engine enters the upper tank 14 through the inlet 15 and thence enters the box 18 of the first section through the opening 17 on the left side. The flow is then to the right in the first section and through the aligned boxes on the right hand side to the second section where the flow is towards the left, the entire volume of flow then going back and forth through the successive sections until it reaches the bottom tank 10 from which

it is delivered to the engine again through the outlet 13.

It will thus be seen that the radiator of this invention is simple and easy to repair and is of high efficiency as a cooling or heating radiator due to the long path of water flow subjected to the action of the air.

We are aware that many changes may be made, and numerous details of construction 10 may be varied through a wide range without departing from the principles of this invention, and we therefore do not purpose limiting the patent granted hereon, otherwise than necessitated by the prior art.

15. We claim as our invention:

A sectional automobile radiator comprising top and bottom tanks, a plurality of interchangeable sections arranged therebetween, every one of said sections comprising a tube 20 having flattened ends each entered and expanded in a solid block apertured to receive one end of the tube, the block at one end having an unobstructed passage opening at its upper face communicating with said tube, the 25 block at the other end having an unobstructed passage opening at its lower face communicating with said tube, said sections being positioned adjacent each other with the passage in one block communicating with the passage 30 in an adjoining block, whereby said sections are connected in series and water may circulate freely from section to section, and bolts passing through said blocks and at opposite ends thereof and engaging said tanks 35 for securing said parts together in assembled relation.

In testimony whereof, we have hereunto subscribed our names at Chicago, Cook county, Illinois.

40 CLAUDE D. LARMER.
BENJAMIN E. DETTMAN.
